LATERALLY TRAVERSING VERTICAL BLIND

Clifford E. Peck, Indianapolis, Ind.

Application May 3, 1951, Serial No. 224,377

2 Claims. (Cl. 160—168)

1

This invention relates to a blind of the louver type wherein the louvers are vertically positioned when used as a blind for a window in the usual manner, and particularly to means for rocking the louvers on vertical axes, and also causing the louvers to travel horizontally to provide for a clear, unobstructed opening between adjacent groups of louvers.

A primary object of the invention is to provide a structure of the nature indicated above wherein the louvers may be caused to rock on their vertical axes by a positive, rigid mechanical connection, that is rigid as opposed to the heretofore commonly employed ladder tape construction and cord connections such as have heretofore been employed in the so-called Venetian blinds. In the invention herein set forth, each louver in the blind is mounted independently of an adjacent louver, but there is a mechanical interconnection causing the louvers to rock in unison to the degree desired.

A further primary object of the invention is to provide a mechanism which will cause the louvers regardless of the positions to which they may have been rocked in respect to their vertical axes to move bodily one in relation to a next adjacent louver whereby the spacing of the axes of the respective louvers will be varied in accordance with the opening desired.

A still further important object of the invention resides in the particular structure which is employed to mount the louvers by end connections so that they may be readily disconnected and removed as may be desired, or without having to disturb any of the mechanism which causes the louvers to rock or to travel.

Further objects and advantages of the invention will become apparent to those versed in the art in the following description of one particular form of the invention as illustrated in the accompanying drawings, in which

Fig. 1 is a view in inside elevation of a structure embodying the invention, showing the louvers in a "closed" condition;

Fig. 2 is a view in horizontal section on the line 2—2 in Fig. 1;

Fig. 3 is a view in side elevation on an enlarged scale of a louver end mounting;

Fig. 4 is a vertical section on the line 4—4 in Fig. 3;

Fig. 5 is a view in vertical section on the line 4—4 in Fig. 3, but with the elements in disassembled position initially placed for the inter-engagement thereof;

2

Fig. 6 is a view in rear elevation of a louver attaching clip;

Fig. 7 is a front view in elevation of the attaching clip;

Fig. 8 is a view in section on the line 8—8 in Fig. 1;

Fig. 9 is a view in section on the line 9—9 in Fig. 1;

Fig. 10 is a detail in side elevation and partial section of a louver rotating mechanism;

Fig. 11 is a view in vertical section on the line 11—11 in Fig. 10;

Fig. 12 is a view in transverse section on the line 12—12 in Fig. 11;

Fig. 13 is a view in top plan of the structure;

Fig. 14 is a detail in section on the line 14—14 in Fig. 13, on an enlarged scale;

Fig. 15 is a view in section on the line 15—15 in Fig. 13 on an enlarged scale;

Fig. 16 is a view in vertical section on the line 16—16 in Fig. 13 on a still further enlarged scale; and

Fig. 17 is a diagrammatic representation of the louver traversing drive.

While the invention has other uses, it will be described herein in reference to use as a window blind. The structure when viewed from the inside of the room looking toward the window will appear as indicated in Fig. 1, wherein there is a top facia 20, a lower facia 21, and appearing therebetween will be the louvers generally indicated by the numeral 22.

In the form of the invention herein shown, the louvers 22 are mounted in two groups, whereby the louvers may be parted in the center to be pulled from the central zone to each side of the window for a clear opening therebetween. While the invention is not restricted to any definite number of louvers in each group, the invention is illustrated herein to have the louvers 23—28 in one group and the louvers 29—34 in a second group, the louvers 28 and 34 overlapping at their adjacent vertical edges. The louvers 28 and 34 overlap in their closed positions as indicated in Figs. 1 and 2.

All of these louvers 22 are mounted to turn on vertically disposed axes. A lever 35, Fig. 1, is rockably engaged with a vertically disposed rod 36 on the left hand side of the blind, and by raising the lever 35 and rocking it through the dash line position as indicated in Fig. 2, all of the louvers 23—28 may be rocked to their dash line positions. Likewise there is a lever 37 rockably mounted on a rod 38 at the right hand side 55 of the blind, and by rocking it through its dash

line of travel as indicated in Fig. 2, the louvers 29-34 may be rocked to their dash line positions. The details of this mechanism in each case will be described below.

On each side of the blind there is provided a cord 93 and 46 respectively, with a hand grip 41 and 42. By moving these grips up and down, the louvers 22 may be caused to travel laterally of the blind so as to give the desired clear opening between the inner louvers 28 and 34, or the louvers having been open, may be pulled back to the closed positions as indicated in Figs. 1 and 2. These operations may be conducted either in their solid line positions or in the dash line positions, Fig. 2. The mechanism for this operation will also be described below in detail.

The entire mechanism is mounted at the window opening in any suitable manner depending upon the construction of the framework about the window. In the form herein shown, the structure involving the invention is mounted on a frame 43 which is shown as an angle iron frame.

Referring to Figs. 13, 15, and 16, there is a downturned end plate 44 at the upper left-hand corner of the frame 43, and supported therefrom by the leg 45, Fig. 16. As illustrated primarily in Fig. 15, there is a gear bracket 46 supported from the end bracket 44 by any suitable means, herein shown as by a stud 47a. The bracket 46 has a gear hub 47 revolubly carried thereby, and a shaft 48 extends through the hub 47 with a driving connection therewith. This shaft 48 may have a number of different cross-sectional shapes, the important thing being that the shape be such that by inserting it through the hub 47, and rotating the shaft 48 on its axis, the hub 47 will be driven therewith. In the present showing, this shaft 48 is shown to be square in cross-section.

The shaft 48 extends from the hub 47 to a central bracket 49, Figs. 13 and 14, where the shaft extends by one end revolubly through a downturned leg 50. The shaft 48 is secured to the hub 47 in respect to longitudinal travel, herein shown as by means of a pin 51 passed through the hub 47 to the left of the bracket 46. The hub 47 is provided with a shoulder 52 on its one side, and a collar 53 surrounds the hub 47 on the other side of the bracket 46 and is secured in place by means of the pin 51, all to the end that the hub 47 may revolve in respect to the bracket 46 but may not travel in a direction longitudinally of the shaft 48.

The bracket 46 has a horizontally disposed leg 54, through which extends vertically a tubular louver carrier 55. This carrier 55 is provided with an annular collar 56 to abut the underside of the leg 54, and a gear 57 is fixed on the upper end of the carrier 55 on the topside of the leg 54, so that the carrier 55 is held against vertical displacement in respect to the leg 54. On the hub 47 is fixed a pinion gear 58 to be in constant mesh with the gear 57.

The bracket 46 has an upper leg 59 turned over and above the gear 58, and to this leg 59 there is rockably attached an end of a lazy tongs 60.

The same structure is duplicated at the lower left hand portion of the frame 43 wherein there is an end bracket 61 to which a gear bracket 62 is attached to support one end of the shaft 63 to extend longitudinally therefrom to be revolubly carried through the leg 64 of a center bracket 65. The bracket 65 corresponds in all respects to the bracket 49 but has its leg 64

turned upwardly instead of downwardly as is the leg 59. From the bracket 62 there extends upwardly a louver carrier 66.

In the present showing, the rod 36 is square in section, and its upper and lower ends fit respectively into sockets 67 and 68, each secured in turn to the louver carriers 55 and 66. Thus by rocking the rod 36 on its vertical axis, the upper and lower shafts 48 and 63 are caused to rotate on their respective horizontal axes.

Spaced along the respective shafts 48 and 63, are a plurality of louver carriers generally designated by the numerals 69 and 70. There is a pair of louvers 69, 70 for each of the louvers 24, 25, 26, 27, 28, the carriers 54 and 68 being provided to support the first louver 23. These carriers 69, 70 are mounted to travel longitudinally of their respective shafts 48 and 63. In each instance, the traveling louver is mounted as indicated in Figs. 10-12 wherein the illustrations apply to the lower louver 70 but are exactly the same in construction for the upper louvers 69, the only difference being that the carriers in each instance are directed one toward the other, that is the upper carriers 69 are directed downwardly whereas the lower carriers 70 are directed upwardly.

Referring now to Figs. 10-12, a louver carrier 70 is provided with an annular shoulder 71 which rests on the outer side of a leg 72 extending laterally from a vertically disposed bracket member 73 which in turn revolubly carries a gear hub 74. The gear hub 74 is held against longitudinal travel through the member 73, but has the shaft 63 slidable through the hub 74, but in rotary driving connection therewith. The hub 74 is provided with a reduced diameter section 75 which extends through the member 73, to carry a collar 76 on the other side of the member 73 as the means for restraining the hub 74 against travel laterally through the member 73. On the face of the hub 74 is secured a pinion gear 77 which is in constant mesh with a gear member 78 fixed to the underside of the carrier 70 in such manner as to prevent the carrier 70 from being lifted vertically from the leg 72.

The gear member 78 is herein shown as consisting simply of a plate through which there are holes 79 to receive the teeth 80 of the pinion gear 77. This makes a relatively cheap construction which may be stamped instead of having to be milled or formed in the usual manner, there is a laterally turned foot 73a to the underside of which is secured the lazy tongs 81. The lazy tongs 81 is a duplicate of the top lazy tongs 60. In each instance, the lazy tongs consist of a plurality of cross links 82 and 83 pivotally connected by the outer ends and also pivotally connected by their central crossing over portions by screws 84 which are secured to the foot 73a in each instance. Thus, the lazy tongs 60 on top and 81 underneath are secured to the fixed gear brackets 46 and 62 and to the shiftable gear brackets supporting the carriers 69 and 70 spaced along the respective shafts 48 and 63, whereby contraction of the lazy tongs as indicated in Fig. 13 will pull the carriers one toward the other into close proximity, and the under lazy tongs 81 will likewise pull the lower carrier 70 into close proximity adjacent the fixed end brackets 46 and 62 respectively.

To effect this traversing travel of the respective carriers 69 and 70 there is provided a continuous length of a cable or cord 85. This cable 75 85 is looped around a pulley 86 carried on a ver-

tical axis on the side of the leg 50 of the bracket 49, Figs. 13 and 14, and thence extends to the left to have the run 87 engaged by a clamp 88 which is secured to the outer right hand screw 89 passing through the ends of the lazy tongs 60. This run 87 is carried to the left over a pulley 90, vertically downwardly therefrom, to carry under a lower pulley 91 horizontally to a central pulley 92, around that pulley 92, back through a run 93 to be engaged by a clamp 94 secured to the end screw 84 at the outer right hand end of the lazy tongs 81, to the pulley 95, then upwardly vertically to have the end grip 41 fixed thereon, and finally around over the pulley 96 back to the pulley 86, Fig. 17. By pulling downwardly on the hand grip 41, the cable will cause the lazy tongs 60 and 81 to be extended, to cause the cable to travel in the directions of the arrows, and thereby carry the louvers 24-28 to their fully spaced apart positions.

Now, where it is intended to have the louvers separate, one group from the other as indicated above, to provide a central clear opening therebetween, the above construction is duplicated to traverse the right hand portion of the opening through the frame 43. In this regard, there is the upper drive shaft 98 and a lower drive shaft 99 each having mounted thereon respectively the louver carriers 100 and 101.

To rock the louvers 23-28 from their closed or overlapping relationship as indicated in Figs. 1 and 2, the shaft 48, 63 on the one side and 98, 99 on the other side, are caused to rotate on their axes through the vertically disposed rods 36, 33 respectively. Now that motion is transmitted through the respective louver carriers in the following manner.

The louvers may be made out of any desirable material, such as metal, wood, but preferably they are made out of a fabric which is flexible, and which may be replaced from time to time for purposes of cleaning or even different color combinations as the interior decorating scheme may warrant. In the present showing, these louvers are of fabric, therefore their ends have to have a special engagements with the various carriers 69, 70 and 100, 101. In this regard, reference is made to Figs. 3-7 inclusive, wherein there is shown a plate 102 of an elongated nature and having a horizontally disposed slot 103 therethrough traversing the major length thereof.

An elongated spring clip 104 is shaped to have a generally circular cross sectional body 105 having a longitudinal opening 106 entirely across its length, whereby the sidewalls of the clip body are carried toward each other to form the margins of the opening 106 and then turn outwardly into the diverging feet 107 and 108, as best indicated in Fig. 5. The diameter of the body 105 is approximately the vertical dimension of the slot 103.

A length of fabric 109a is laid across a side face of the plate 102, across the slot 103, and the clip 104 is brought up with its rounded body 105 to carry the fabric through the slot 103 by pressing the clip firmly thereagainst, to permit the clip to enter through the slot with the fabric wrapped around the body 105 until the feet 107 and 108 form the limiting stop. The shape of the clip 104 is such that the fabric will be snugly gripped against the upper and lower margins of the slot 103 by the clip. Then after the full insertion of the clip 104, Fig. 4, the fabric is wrapped around and pulled downwardly as indicated in Fig. 4. In this manner the feet 107

and 108 are completely covered over, and so is the body 105 by the enclosing fabric on the other side of the plate 102.

The plate 102 is provided with a rectangular tongue 109 extending therefrom in the plane of the plate 102. The end of the tongue 109 is provided with an opening 110 therethrough. The tongue 109 is inserted through each of the respective louver carriers, through a rectangular opening 111 in an outer end thereof, to extend within the bore of the carrier, Fig. 10, to receive a spring 112 therearound, to have the lower end of the spring 112 inserted and carried through the hole 110. The upper end of the spring in respect to Fig. 10, bears against the closed end 113 of the carrier 70 through which the opening 111 extends. The spring 112 is a compression spring thereby tending to pull the tongue 109 into the carrier in each instance.

Thus when the louver fabric is engaged with the respective plates 102, that is the one at the top and the one at the bottom, the springs 112 tend to hold the fabric tautly.

The louver carriers 100 and 101 supporting the louvers 30-34 are caused to shift transversely of the window by means of the cable 40 operated by the hand grip 42. This cable 40 is carried upwardly over the top pulley 115, to extend to the central pulley 116 carried by the bracket 49, Figs. 13 and 14, to have the cable 40 engaged by the clamp 117 at the outer end of the lazy tongs 118 (herein shown as in the extended position) by the screw 181, and from the pulley 116, the cable pulley extends to the right again over the pulley 119 and then downwardly to a lower pulley 120, horizontally across to a center pulley 121, thence horizontally to the right again around the pulley 122 and thence in the vertical run back to the pulley 115.

Thus is to be seen that I have provided a structure wherein the louvers may be run on their vertical axes to give the maximum amount of light entrance therewith, or they may be rocked to their fully closed or overlapping position. Then regardless of the degree of rocking of the louvers on their vertical axes, the louvers may be shifted from their central positions or rather their most extended positions in respect to the ends of the structure away from the center to come into close compacted relationship. There are no ladder tapes or other flexible interengagements between the louvers, but instead they are fixed at their extreme outer ends to carriers which are mechanically moved. Also it is to be seen that the individual louvers may be quickly replaced and installed without disturbing any of the other mechanism.

In some installations, the shafts 48, 63, and 98, 99 may have such length that they may tend to sag between their end supports. To support these shafts intermediate those ends, a pair of side plates 150 and 151, Figs. 1 and 8, are provided to be mounted upon a bracket 159 which is supported from the frame 43. These side plates 150 and 151 are rigid, and in the present showing are inclined upwardly and inwardly one toward the other to have inturned marginal portions 153 and 154 lapping over the various brackets carried on the lower shafts 63 and 99, herein shown as lapping over on the top sides of those brackets whereby the brackets may slide along those members 153 and 154. Then the brackets carry on the overturned leg 72, a pair of fingers 155 and 156 to pass over the topsides of those members 153 and 154 so that the brackets 73 may not drop

downwardly, by reason of the interengagement of the end portions 153 and 154 of the side plates 150 and 151. Consequently the shafts 63 and 99 are supported through the brackets 73 against a tendency to bend between their end supports.

In like manner, side plates 163 and 164 are mounted on a bracket 162 carried by the frame 43 to be angularly directed inwardly and downwardly to have inturned edge portions 163 and 164 overlapping the upper line of brackets 54 carried on the two shafts 48 and 98. These brackets have the two pairs of fingers 165 and 166 extending across the undersides of those plate end portions 163 and 164 so that the upper shafts 48 and 98 are thereby supported through the brackets and in turn by the side plates 160 and 161. The side plates in each instance, serve also as a housing to conceal the mechanism of the brackets and the lazy tongs which appear within the confines of those plates.

The facia 20 and 21 are carried by the upper and lower brackets 162 and 159 respectively in any suitable manner, Fig. 16, herein shown as by turned legs 170 and 171 respectively, the leg 170 being downturned and the leg 171 being upturned, the respective free ends of these legs being inserted within a groove 172 and 173 respectively on the inside opposing marginal portions of the facia members. Then there is extended from each of these legs 170 and 171 a slideable bar 174 and 175 respectively secured on the inner sides of the legs by the screws 176. The ends of these bars are carried into upper and lower grooves 177 and 178 respectively so that the facia in each instance is supported between the outer ends of the legs and the bars.

Therefore, while I have described the invention in more or less minute detail in respect to one particular use, it is obvious that structural variations may be employed such as in the means for contracting or expanding the lazy tongs structure, and in other details, all without departing from the spirit of the invention, and I therefore do not desire to be limited to that precise form any more than may be required by the limitation of the following claims.

I claim:

1. A multiple slat blind comprising a pair of spaced apart parallel shafts; means revolvably supporting said shafts in fixed longitudinal positions; a plurality of brackets mounted on said shafts to have the shafts extend revolvably therethrough and the brackets shiftable therealong; a carrier mounted on each of said brackets to be revolvable on axes normal to the shafts, the carriers of brackets on one shaft being directed toward carriers of brackets on the other shaft; a drive member carried by the bracket in each instance to be revolved by rotation of the shaft; a driven member carried by said carrier in each instance to be in driving engagement with the driving member, whereby rotation of the shafts cause rotation of the carriers; means interengaging the ends of the slats with said carriers to have the slats extend from the brackets in substantial parallelism one slat with another; means maintaining said brackets in uniform spacing one from the other along each of said shafts; said means comprising a lazy tongs having its ends secured

to end brackets on each shaft, and its intermediate cross member intersections secured one each to each bracket between said end brackets; a common end bracket on each shaft being fixed against travel along, and rotation about the shaft; and means independent of rotation of the shaft for expanding and contracting said lazy tongs to vary said bracket spacing comprising an endless cable having spaced portions fixed to that end of said lazy tongs in each instance removed from said fixed end bracket; a pulley at the extreme end of expansion of said lazy tongs in each instance; and pulleys at said fixed bracket in each instance; said cable being carried around said pulleys by parallel flights along said shafts and by continuous parallel flights between said shafts, whereby travel of the cable around the pulleys in one direction will expand both lazy tongs and in the other direction will retract both lazy tongs; said lazy tongs being fixed against revolution about said shafts.

2. A Venetian type blind having a plurality of vertically disposed slats comprising a pair of vertically spaced horizontally disposed shafts one each at the top and bottom of said slats; gear means between said shafts and said slats driven by the shafts for rotating the slats on vertical axes upon rotation of the shafts; and lazy tongs supported in fixed planes against revolution about said shafts, one at each of said shafts and interconnecting with each of said slats as means for spacing apart said slats along said shafts; a bracket at each end of each of said slats rotatably supporting said slats; said shafts rotatably extending through said brackets; said gear means being supported by said brackets; and said lazy tongs being pivotally attached to said brackets; and guide means slidably supporting and vertically spacing apart said brackets of the respective spaced apart shafts; means for rocking said shafts for said rotation thereof; and means for extending and contracting said lazy tongs independently of rotation of said shafts comprising an endless cable having spaced portions fixed to that end of said lazy tongs in each instance removed from said fixed end bracket; a pulley at the extreme end of expansion of said lazy tongs in each instance; and pulleys at said fixed brackets in each instance; said cable being carried around said pulleys by parallel flights along said shafts and by continuous parallel flights between said shafts, whereby travel of the cable around the pulleys in one direction will expand both lazy tongs and in the other direction will retract both lazy tongs.

CLIFFORD E. PECK.
